(Cl. D26—14)

To all whom it may concern:

Be it known that I, Emil C. Steinbach, a citizen of the United States, residing at Chicago, in the county of Cook and State of Illinois, have invented a new, original, and ornamental Design for Wire Magazine, of which the following is a specification, reference being had to the accompanying drawing, forming a part thereof.

In the drawings:

Figure 1 is a front elevational view of a wire magazine, showing my new design;

Figure 2 is a plan view thereof;

Figure 3 is a rear elevational view thereof; and

Figure 4 is an end elevational view thereof.

I claim:

The ornamental design for a wire magazine, as shown.

EMIL C. STEINBACH.
